MARTIN C. ALBERTSEN, OF MINDEN, NEVADA, ASSIGNOR TO CORRIDON H. PUTNAM,
OF AZUSA, CALIFORNIA.

PICK-UP FOR SHOCK LOADERS.

Application filed March 2, 1925, Serial No. 12,726. Renewed May 12, 1928.

This invention relates to improvements in shock loading machines particularly adapted for use in connection with harvesters or the like.

5 An important object of the invention is to provide a loading machine in which a rotary or gathering mechanism engages shocks, hay or the like from the ground and deposits the same on suitable conveying 60 means.

A further object of the invention is to provide a loading machine of the above character which is simple and compact in construction and which can be manufactured 15 at a comparatively low cost.

A still further object of the invention is to provide a loading machine of this character which may be readily mounted upon the conventional type of harvesters or like 20 machines.

Other objects and advantages of this invention will be apparent during the course of the following description.

In the accompanying drawings forming 25 a part of this specification and in which like numerals are employed to designate like parts throughout the same:

Figure 1 is a side elevation showing my improved device mounted in connection with 30 suitable conveying mechanism,

Figure 2 is a top plan view of the same, Figure 3 is a vertical sectional view taken through the rotary mechanism,

Figure 4 is an enlarged front elevation of 35 a portion of the same,

Figure 5 is a vertical sectional view through the same, and

Figure 6 is a transverse sectional view taken on the line 6—6 of Figure 4.

40 In the drawings, wherein for the purpose of illustration is shown the preferred embodiment of my invention, the numeral 10 generally indicates an inclined frame adapted to permit elevation of the grain or other material for loading into a suitable conveyor. This frame includes suitable floor boards 11 carrying side boards 12 adapted to prevent displacement of the material. The extreme edges of the lower portion 45 of the floor boards are provided with projections 13, the purpose of which will be hereinafter more fully described. A transverse shaft 14 is rotatably mounted beneath the inclined frame 10 near the lower extremity thereof, this shaft carrying a pair of 50

sprockets 15 on each projecting extremity. A pair of main drive chains 16 are trained over these outermost sprockets and drive sprockets mounted upon carrier wheels or any suitable drive means. An inner pair of 60 sprockets 17 are secured to the shaft 14 and are positioned within the side boards of the inclined frame, suitable chains 18 being trained about these inner sprockets and over suitable sprockets at the upper extremity of the frame, (not shown). The inner chains 18 carry a plurality of cross slots 19 thus providing a movable conveyor.

The structure thus described is common to most forms of grain gathering machines and 70 therefore I do not wish to claim any part thereof. My invention relates more specifically to a rotary mechanism for engaging the shocks or other form of grain and depositing same upon the movable conveyor 75 whereby it is elevated and deposited in a suitable wagon body.

Referring now to the elements comprising my invention, the numeral 20 designates a pair of angular reel supports bent to suitably engage the side boards of the inclined frame and project slightly outward at the extremity. These brackets are adapted to support a pair of stub shafts 21 rotatably mounted upon the brackets or supports to 80 provide means about which the reel mechanism revolves. The gathering reel generally denoted by the numeral 22 comprises a pair of end discs 23 having formed at the central portion outwardly extending bearing 85 sleeves 24. These sleeves fit snugly about the stub shafts 21 and permit convenient operation of the reel. The bearing sleeves 24 are enclosed by a pair of outer journal sleeves 25 which are retained in a stationary 90 position by collars 26 positioned about the sleeves and secured thereto by means of set screws 27. Formed on the lower portions of the collars 26 are transversely positioned bracket sleeves 28 adapted to engage the 95 angular supporting brackets 20. A pair of sprocket wheels 29 are mounted on the outer extremities of the bearing sleeves 24 being secured thereon by means of set screws 30 or any suitable manner. These sprockets are 100 driven by continuous chains 31 trained over the sprockets 29 and the intermediate sprockets carried by the transverse shaft 14, adapted to rotate the reel. The extreme 105 ends of the stub shafts 21 carry a pair of 110

upwardly directed bracket arms 32, the lower extremities thereof being provided with openings for engaging the extremities of the shaft and secured thereon by cotter pins or the like. The upper extremities of these arms are apertured and engage the angular extremities of a pair of braces 33 the opposite extremities of which are bolted to the side boards of the inclined frame 10. 10 This construction is provided to render the stub shaft immovable permitting rotation of the bearing sleeves 24 thereon.

The framework of the reel between the discs is composed of a plurality of longitudinal rods 34 threadedly mounted in or otherwise secured to the discs and positioned adjacent the peripheral edge thereof. A pair of cranks 35 are secured to the inner extremities of the stub shafts 21, crank pins 36 formed on the extremities thereof forming eccentric bearings about which the grain engaging elements operate. It is desirable that the crank pins 36 be positioned forwardly of and in a horizontal plane with the 25 disc centers in order that the engaging mechanism may function with the greatest efficiency.

In the present embodiment illustrating one form of my improved loading reel I 30 employ six cross rods 34 which will permit the use of three prong carrying bars 37 adapted to operate through alternate cross rods. The bars 37 are preferably rectangular in cross section and are adapted to rotate 35 eccentrically in relation to the central axis of the discs 23. The mechanism adapted to operate the bars comprises three link arms 38 rotatably mounted upon the crank pins 36 and secured against displacement by suitable cotter pins mounted in the extremities 40 of these pins. The opposite extremities of these arms are pivotally connected with extension pins formed upon a series of V-shaped levers 39. Each of the V-shaped levers 39 is provided with an opening 45 adjacent the extremity of one of the projecting arms, in order to engage alternate cross rods. The levers are retained in position upon the cross rods by means of spacing sleeves 40 positioned on the extremities 50 of the rods between the levers and the discs. The third projection arm of each of the V-shaped bell crank levers is secured to an extremity of the carrier bars 37, it being 55 understood that the V-shaped levers are arranged in directly opposed relation upon the cross rods 34 and therefore actuate the carrier bars in parallel relation to the rods.

It is to be noted that my improved loading mechanism may be readily mounted upon the conventional type of harvesters without material alteration in the construction thereof or in any manner obstructing the efficient 60 operation of the machine. My improved loading device is designed to facilitate the

gathering of grain in shocks or any other form without bruising or, in any manner subjecting the material handled, to undue abuse. The grain is engaged by a plurality of tines or rake teeth 41 arranged in alignment upon each carrier bar. These tines project from the bars and are preferably arranged in staggered relation upon the several bars. In the embodiment shown and described the tines comprise straight pointed 75 members but it is contemplated that they may be arcuate in form for numerous uses of the mechanism.

In operation, the carrier bars and tines mounted thereon are so arranged that the 80 rake teeth will extend in angular manner at the point of engagement with the shock enabling the teeth to firmly engage the shock due to their upwardly inclined position and carry it over the reel, the teeth being caused 85 to move toward the center axis of the discs when approaching the rear of the reel and disengage the shock. It is obvious from the arrangement of the link arms and bell crank levers that the carrier bars and tines or 90 teeth secured thereto will project to the outermost position during the forward movement due to the eccentric position of the link arm crank pins. This will necessarily cause the teeth to positively grip the grain 95 as it comes in contact with the reel causing it to be thrown over on to the conveyor frame. As the grain is lifted by the teeth and deposited upon a traveling conveyor the teeth are withdrawn from the shock by 100 movement of the carrier bars relative to the stationary cross rods. This operation will become apparent from the enlarged sectional view of the reel mechanism as clearly illustrated in Figure 3.

It is to be understood that the form of my invention herewith shown and described is to be taken as the preferred example of the same, and that various changes as to the shape, size and arrangement of parts may be resorted to without departing from the spirit of the invention or the scope of the subjoined claims.

By the term "triangular" as used in the claims, I mean to convey the idea that the 115 three points, namely, the pivot of each rocker lever 39 on the drum head, the point of connection of the link 38, and the longitudinal axis of the fork bar, form a triangle (see Figure 3). It will be noted, however, 120 that the fork bar is set back or inwardly on the lever so as to give sufficient length to the teeth 41. The relation of these parts is such that the plane in which the teeth project outwardly crosses the imaginary line 125 that connects the pivot of the lever 39 with the point of connection of the link 38 to the lever 39.

Having thus described my invention, I claim:

1. In a device of the character described, a rotatable drum including end members, concentric pivot means for rotatably supporting the drum, approximately triangular levers arranged generally radially adjacent to the end members, and having their bases arranged outermost, means pivotally connecting the bases of the levers with the end members adjacent to corresponding sides of the levers, pivot means disposed eccentrically with respect to the first named pivot means, links pivotally attached to the eccentric pivot means and with the bases of said approximately triangular levers adjacent to the opposite corresponding sides thereof, teeth carrying bars mounted upon the approximately triangular levers adjacent their inner apexes, and means to rotate said drums.
2. In a loading device of the character described, a drum, concentric means for rotatably supporting the drum, generally radial levers, means pivotally connecting the outer ends of the levers with the drum, pivot means disposed eccentric with relation to the axis of rotation of the drum, links connected with the eccentric pivot means and pivotally connected with the outer ends of the radial levers at points spaced laterally from the pivotal supports of said levers, teeth carrying bars rigidly attached to the inner ends of said levers and bodily shiftable therewith, and means to rotate the drum.
3. In a loading device of the character described, a rotatable drum including a pair of ends, spaced rods extending longitudinally of the drum and connecting said ends, approximately V-shaped levers arranged generally radially upon the sides of the ends and having their bases disposed outermost, corresponding arms of the V-shaped levers being pivoted upon alternate rods, pivot means disposed eccentric with relation to the axis of rotation of the drum, links pivotally connected with the eccentric pivot means and pivotally connected with the corresponding opposite arms of the V-shaped levers adjacent to their bases, and teeth carrying bars rigidly attached to the approximately V-shaped levers adjacent to their apexes.
4. In a device of the kind described, the combination of a drum mounted to rotate on a longitudinal axis, a plurality of rockers mounted in oppositely disposed pairs, each pair of rockers having aligned pivotal supports on the drum at a point removed from the axis of rotation of the drum, links corresponding to each pair of rockers with a pivotal connection at one end connecting the same to corresponding pairs of rockers, a relatively fixed pivotal support for the other end of each link, eccentric to the axis of rotation of the drum, a fork-bar connecting each pair of rockers, located between the axis of the drum and the pivotal supports of the rockers and displaced inwardly with respect to a line connecting the pivotal supports of the rockers with their points of attachment to the links, and forks carried by the fork-bars projecting in a plane extending outwardly across the said line.

In testimony whereof I affix my signature.

MARTIN C. ALBERTSEN.
